UNITED STATES PATENT OFFICE.

HERBERT BROWN, OF ROCHFORD, SOUTH DAKOTA.

LEVELING DEVICE.

No. 852,013.

Specification of Letters Patent.

Patented April 30, 1907.

Application filed May 31, 1906. Serial No. 319,595.

To all whom it may concern:

Be it known that I, HERBERT BROWN, a citizen of the United States, residing at Rochford, in the county of Pennington and State of South Dakota, have invented certain new and useful Improvements in Leveling Devices, of which the following is a specification, reference being had therein to the accompanying drawings.

10 This invention relates to improvements in plumb levels for use on engineers' transits.

One object of the invention is to provide a simple and practical device of this character which will enable the operator to read 15 angles, run grades, etc., without the use of a templet.

Another object of the invention is to provide a device of this character which may be used as an attachment for an engineer's 20 transit to take the place of the usual altitude arc and the leveling glass under the telescope, and to enable the operator to read vertical angles without first leveling his telescope.

Further objects and advantages of the invention, as well as the structural features by 25 means of which they are attained, will be made clear by an examination of the following specification, taken in connection with the accompanying drawings, in which,

30 Figure 1 is a side elevation of the improved level; Fig. 2 is a vertical transverse sectional view through the same; Fig. 3 is a detail horizontal sectional view; Fig. 4 is a vertical transverse sectional view through the device 35 showing it in the form of an attachment secured upon the telescope axis of an engineer's transit; and Fig. 5 is a detail view showing the clamping arms and their operating screw-rod.

40 Referring to the drawings, the numeral 1 denotes the improved leveling device which, as shown in Fig. 1, is mounted in an opening in a level block or body 2, and, as shown in Fig. 4, upon the telescope axis 3 of an engineer's transit. The level 2 may be of any 45 suitable form and construction, and the device 1 may be mounted in any suitable manner upon or within it. The device 1, as shown in Figs. 1, 2 and 3, comprises a body 4 formed at its center with a transverse opening 5 and at its ends with attaching ears 6, the latter being apertured to receive screws 7 which secure the device in the level 2. The 55 opening 5 is closed at one end by a ring or bezel 8 and at its opposite end by a ring or

bezel 9, said rings or bezels being provided with glasses or crystals 10, as shown. The bezel 9 has internal screw threads to engage external threads upon an annular projecting portion 11 of the body 4. The bezel 8 has 60 external screw threads to engage internal threads in the body 4, and between the inner end of the bezel 8 and an annular shoulder 12, formed in the opening 5, is retained a dial ring 13 which has its opposite faces graduated in degrees and half-degrees, as shown at 65 14. This graduated ring or arc is adjusted by means of a screw 14^a mounted in the upper part of the projecting portion 11 of the body 4 and in an arm 15 projecting outwardly from the ring 13, said screw having its collar held in place by the screw bushing 16, as shown in Fig. 3.

Coacting with the graduated dial ring or arc 13 is a double vernier in the form of a 75 swinging pointer 17 pivotally mounted intermediate its ends and having its lower end weighted, as shown at 18, and its segmental-shaped upper end bifurcated to receive the inner edge of the dial ring 13 and to form the 80 two verniers 19, which latter are graduated, as shown, or in any other suitable manner. The weighted end 18 of the body portion 17 of the double vernier causes the latter to 85 hang perpendicular or plumb at all times upon its pivot 20 which is preferably in the form of a tempered steel shaft. Said shaft has its tapered ends seated in jeweled centers 21 provided in adjusting screws 22, the latter being located in forked brackets or 90 posts 23 which project upwardly or inwardly from the body 4 and the bezel 8. In order to hold the double vernier in any position, clamping arms 24, 25 are provided upon its 95 opposite sides and are adjusted toward and from each other and the body portion 17 of the double vernier or plumb, said arms having upon their inner ends inwardly projecting jaws 26 which are apertured to permit the pivot 20 to pass freely therethrough. 100 These arms 24, 25 are adjusted toward and from each other by means of a screw rod 27 which is disposed in alining openings in the body 4 and the bezel 8. The rod 27 passes through an opening in the arm 25 and has 105 adjacent to one end a shoulder 29 to engage said arm. The opposite end of said rod is formed with screw threads 30 to engage a screw-threaded opening in the other arm 24. The screw threads 30 are also engaged by a 110

thumb nut 31 by means of which the screw rod 27 may be operated to adjust said clamping arms. Said rod may also be adjusted by a similar thumb nut 32 upon screw threads 5 33 at its opposite end.

The embodiment of the invention shown in Fig. 4 is in the form of an attachment for the telescope axis 3 of an engineer's transit (not shown), and it is very similar in construction and operation to the form of the invention just described. As shown in Fig. 4, a circular plate or head 35 takes the place of the bezel 8 and has at the center of its rear or outer face a screw-threaded socket 36 to receive the threaded end of the telescope axis 3. The thumb nut 31 is omitted and the screw rod 27 is adjustable only from its front or outer end by means of the nut 32. The weight carries but one vernier and the body 20 4 is also preferably made cylindrical in form and smaller, as will be readily understood.

From the foregoing description, taken in connection with the accompanying drawings, it is thought that the construction, use 25 and advantages of the invention will be readily understood without a more extended explanation.

Various changes in the form, proportion and the minor details of construction may be 30 made without departing from the spirit or sacrificing any of the advantages of the invention, as defined by the appended claims.

Having thus described my said invention, what I claim as new and desire to secure by 35 Letters Patent of the United States, is

1. A device of the character described comprising a body, a graduated dial therein, a weighted vernier pivotally mounted to coact with said dial, clamping arms to engage 40 said vernier, and a screw rod for operating said clamping arms.

2. A device of the character described comprising a body, a graduated dial therein, a swinging indicator to coact with said dial,

clamps to engage said indicator, and a screw 45 for operating said clamps.

3. A device of the character described comprising a body having an opening therein and means whereby it may be attached to a support, bezels for closing said opening, a 50 graduated dial retained in said opening by one of said bezels, means for adjusting said dial, bearings, a weight pivotally suspended from said bearings, a vernier upon said weight to coact with said dial, and means for 55 clamping said weight against movement, substantially as described.

4. A device of the character described comprising a body having an opening therein and means whereby it may be attached to a 60 support, bezels for closing said opening, a graduated dial retained in said opening by one of said bezels, means for adjusting said dial, bearings, a weight pivotally suspended from said bearings, a vernier upon said 65 weight to coact with said dial, clamping arms to engage said weight, and a screw rod for operating said arms, substantially as described.

5. A device of the character described 70 comprising a body having an opening therein and means whereby it may be attached to a support, bezels for closing said opening, a graduated dial retained in said opening by one of said bezels, a screw for adjusting said 75 dial, bearings, a weight pivotally suspended in said bearings, a vernier carried by said weight to coact with said dial, clamping arms to engage said weight, and a screw rod to operate said arms, substantially as de- 80 scribed.

In testimony whereof I hereunto affix my signature in presence of two witnesses.

HERBERT BROWN.
